Primary Examiner—Janice E. Seeger

(74) Attorney, Agent, or Firm—Womble Carlyle Sandridge & Rice, PLLC

CLAIM

The ornamental design for a furniture post section, as shown and described.

DESCRIPTION

FIG. 1 is a perspective view of a furniture post section of indefinite length showing my new design;

FIG. 2 is a front or side elevational view, the opposite side being a mirror image thereof;

FIG. 3 is a cross section view taken along line 3—3 in FIG. 2 thereof; and,

FIG. 4 is a front elevational view thereof and including broken lines indicating representative environmental elements.

The views of the furniture post section not shown form no part of the claimed design. The broken lines depicting a bedstead in FIG. 3 represent environmental elements only and form no part of the claimed design.

1 Claim, 2 Drawing Sheets
